DOOR OPERATING CONTROL FOR
AUTOMATIC ELEVATORS

Alan M. Hallene, Moline, John J. Drexler, Barstow, and
Henry J. Holuba, Moline, Ill., assignors to Montgomery
Elevator Company, a corporation of Delaware
Continuation of application Ser. No. 258,497, Feb. 14,
1963. This application Nov. 29, 1965, Ser. No. 514,759
6 Claims. (Cl. 187—52)

This application is a continuation of our application Serial No. 258,497, filed February 14, 1963.

This invention relates to an elevator control circuit and more specifically to a control for an automatic elevator wherein the door operation is varied depending upon the demand conditions placed upon the elevator by users thereof.

When an elevator is operated by an attendant who controls the door operation, the number of people entering and waiting to enter or leave an elevator is quickly discernible. The attendant will not close the doors when it is obvious that additional passengers wish to enter or leave. The modern trend is, however, to provide automatic elevators, thus doing away with attendants, but correlated with such elimination, is the problem of providing means for actuating the doors in accordance with the loading conditions. Previously designed circuits for operating automatic elevators have met with varying degrees of success.

It is an object of this invention to provide an improved automatic elevator control circuit.

It is a further object of this invention to provide a control circuit for operating an automatic elevator in accordance with the demands placed thereon.

It is yet another object of this invention to provide in an automatic elevator system a door operation sequence depending upon the presence or absence of passengers in the pathway of the doors.

Accordingly, it is one feature of the invention to provide a control system for an elevator car door apparatus comprising means for controlling the opening, holding open and closing at a first speed of the door, a first safety device coupled to the controlling means actuatable for preventing closing of the door when the latter is held fully open and for causing the door to close at a second reduced speed when an object enters the path of the door and the door is closing at the first speed, and a second safety device coupled to the controlling means actuatable when the door is held open to prevent closing of the door and for opening the door when the door is closing at the first or second speeds.

It is a further feature of the invention to provide in an automatic control system for an elevator car door a timing circuit for holding the door open a first or second period of time.

It is another feature of the invention to provide in an automatic elevator car door control system means for closing the door at a first speed and at a second speed when an object is in the path of the door.

It is yet a further feature of the invention to provide in an automatic elevator door control system at least one dispatching floor position wherein a timing circuit holds the car door open a first time period and a second time period and wherein the timing circuit is prevented from operating at said second reduced timing period at the dispatching floor.

A preferred embodiment of the invention is illustrated in the accompanying drawings, in which:

FIGURE 1 is an across-the-line circuit diagram of the electrical control circuit for the elevator car door; and

FIGURE 2 is a key diagram of the components in FIGURE 1.

2

In the following discussion of the structure and operation of the disclosed embodiment, the following lettered designations will be used for the following items:

5	TFL	Top floor relay.
	1FL	First floor relay.
	EE	Photoelectric relay.
	DOX	Door safety relay.
	TDA	Door time relay.
10	DO	Door open signal relay.
	DE	Door operator pilot relay.
	DT	Door time transfer relay.
	SBR	Shunt brake relay.
	LR	Leveling relay.
15	DOL	Door open limit relay.
	O	Door open power relay.
	DCL	Door close limit relay.
	C	Door close power relay.
	SEC	Safety edge contact.
20	DOPB	Door open push button.
	MLU	Magnetic leveling unit.
	OL	Open limit switch.
	CL	Close limit switch.

25 Relay contacts associated with the relays are assigned the letter abbreviations of the relay, and a number in order, as shown in the key, FIGURE 2, which shows the contacts in the position assumed when the relay is de-energized.

30 Referring now to FIGURE 1, a pair of wires, 1, 2 is shown across which is coupled a source of potential for operating the circuit, in this instance, it is shown as 110 volts alternating current. A pair of leads 15, 16 are coupled to a source of 230 volts direct current for providing driving power to the door motor 18. An elevator selector mechanism (not shown) incorporates a moving brush 3 and stationary contact segments 4a and 4b. Brush 3 makes electrical contact with segment 4a when the elevator is positioned at the top dispatching floor, energizing a relay TFL, and makes electrical contact with segment 4b when the elevator is positioned at the bottom dispatching floor, energizing a relay 1FL.

35 A stepdown transformer 5 supplies reduced voltage to a lamp 6 which projects a beam of radiant energy across the elevator car door opening (not shown) to a photoelectric cell 7a, which is connected to an amplifier 7 coupled across leads 1, 2 containing an output relay contact 7b. When the light beam is shining on the photocell 7a, relay contact 7b is open and a relay EE is de-energized. Whenever the light beam is interrupted, output relay contact 7b of the photoelectric amplifier 7 closes, and relay EE is energized.

40 The elevator car is provided with a door open push-button 25 for the purpose of opening the doors or causing them to remain open when the elevator car is stopped at a floor and is further provided with a pressure-sensitive door edge which causes a contact SEC to close if an object or person is struck by the door edge.

45 An electronic timer 10 is used to determine the time interval during which the elevator doors remain open. Timer 10 is coupled across wires 1, 2 and receives power therefrom. The operating period of this portion of the circuit is caused to time out at different time intervals by changing the circuit resistance between a pair of terminals 10a, 10b. Increasing the resistance between terminals 10a and 10b will lengthen the timing interval whereas decreasing this value of resistance will decrease the timing interval. Electronic timer 10 initiates its timing interval when a closed circuit is established between a second pair of terminals 10c, 10d. Any interruption of the initiating circuit between terminals 10c and 10d causes the timing interval to cease and the timer to be reset. There is

further provided in the timer an output relay contact **10e** which is open before the timing interval is initiated and remains open during the timing interval. Upon the expiration of the selected timing interval, the output relay contacts **10e** closes and remains closed until the initiating circuit between terminals **10c** and **10d** is interrupted.

Other elevator signal circuits (not shown) cause a switch **11** to momentarily close when the car is preparing to stop for a call, and when the operation of a hall call button causes the doors to re-open at a floor where the elevator is standing.

A top terminal dispatcher (not shown) causes a contact **12** to open when the elevator receives the "start down" signal at the top terminal, and a bottom terminal dispatcher (not shown) causes a contact **13** to open when the elevator receives the "start up" signal at the bottom terminal. In addition, a contact **14** associated with the elevator shunt brake contactor (not shown) is open when the elevator is not in motion and is closed when the elevator is running.

A further contact **MLU-1** is associated with a magnetic leveling unit (not shown) on the elevator car and closes as the elevator approaches within a few inches of the floor where it has been required to stop. Contact **MLU-1** remains closed while the elevator remains at the floor and reopens as the car leaves the floor.

The elevator door operating mechanism (not shown) contains an open limit switch, **OL**, and a close limit switch, **CL**. The open limit switch contacts separate when the door reaches the fully open position, and the close limit switch contacts open when the door is closed.

The door operating mechanism is driven by a direct current motor including a shunt field winding **17** and an armature **18**. A speed regulating resistance **19** is utilized to adjust the "normal speed" of the elevator door operation. A second regulating resistor **20** is utilized to adjust the "slow speed" of the door operator motor.

When the elevator car is running through the shaft, shunt brake relay **SBR** is energized through a switch **14** associated with the brake contactor (not shown) and door open limit relay **DOL** is energized through the now closed door open limit switch **OL**.

As the elevator is signaled to stop for a call, switch **11** closes momentarily and energizes door open signal relay **DO** through contacts **SBR-1** and **TDA-1**. Relay **DO** becomes self-holding through contacts **DO-2**, **SBR-1** and **TDA-1**. Door time transfer relay **DT** is energized through contacts **DO-4** and **DCL-1** and becomes self-holding through contacts **DO-4**, **DT-3**, and **EE-3**.

Relay contact **DT-1** closes to connect resistor **8** between terminals **10a** and **10b** of the electronic timer **10**. Relay contact **DT-2** opens to disconnect resistor **9** from terminals **10a** and **10b** of the electronic timer **10**.

As the elevator approaches within a few inches of the floor where it will stop, magnetic leveling unit contact **MLU-1** closes and energizes leveling relay **LR** which closes contact **LR-1**, and door operator pilot relay **DE** is energized through **LR-1** and **DO-3**. In addition, relay contact **DE-2** closes and door open power relay **O** is energized through contacts **C-2**, **DE-2** and **OL**.

Relay contacts **O-2** and **O-3** close to apply voltage across the door operator motor armature **18**, and the door operator motor operates in the opening direction at normal speed. As the doors begin to open, door close limit switch **CL** closes and door close limit relay **DCL** is energized. The car stops level with the floor and shunt brake contactor switch **14** opens to cause relay **SBR** to become deenergized. Relay contact **SBR-1** opens causing relay **DO** to become self-holding through contacts **TDA-1** and **DO-2**. Relay contact **SBR-3** closes and relay **DE** becomes self-holding through contacts **SBR-3**, **DE-1** and **DOL-2**.

When the doors are fully open, door open limit switch **OL** opens deenergizing door open power relay **O** and door open limit relay **DOL**. Relay contacts **O-2** and

O-3 open to disconnect voltage from the door operator motor armature **18** and the door motor stops.

Contact **DOL-1** closes and the initiating circuit between terminals **10c** and **10d** is established through **DOL-1**, **EE-2** and **DO-1**, and electronic timer **10** begins to time out for a first timing interval determined by the value of resistance of resistor **8**. Relay contact **DOL-2** opens and the holding circuit for relay **DE**, including contacts **SBR-3**, **DE-1** and **DOL-2** is broken.

Relay **DE** does not become deenergized, but remains energized through contacts **LR-1** and **DO-3**.

Assuming thereafter that no passengers enter or leave the car so that the photoelectric beam is not interrupted, no further relay operations occur immediately.

At the end of the first timing interval, measured from the time when the doors reach the fully open position, the uninterrupted closure of the electronic timer **10**, initiating circuit between terminals **10c** and **10d**, will cause electronic timer contact **10e** to close. Door time relay **TDA** is energized, contact **TDA-1** opens, and relay **DO** is deenergized.

Relay contact **DO-2** also opens to interrupt the self-holding circuit for relay **DO**. Relay contact **DO-1** opens to interrupt the initiating circuit between terminals **10c** and **10d** of electronic timer **10**; timer contact **10e** immediately opens, relay **TDA** is deenergized, and timer **10** is reset.

Relay contacts **DO-3** and **DO-4** open causing relays **DE** and **DT** to become deenergized. Relay contact **DE-3** closes to energize door close power relay **C**, contact **DT-1** opens to disconnect resistor **8** and relay contact **DT-2** closes to connect resistor **9** across terminals **10a** and **10b** of the electronic timer **10**.

When relay **C** becomes energized, relay contacts **C-3** and **C-5** close to apply voltage to the door operator motor armature **18**. The door operator motor operates in the closing direction at normal speed.

As the doors start closing and leave the fully open position, door open limit switch **OL** closes, and relay **DOL** is energized. When the doors are fully closed, door close limit switch **CL** opens, and relays **C** and **DCL** are deenergized. Relay contacts **C-3** and **C-5** open to disconnect voltage from the door operator motor armature **18** and the door operator motor stops.

Operating the pressure-sensitive safety edge contact **SEC** or the door open push button **25** while the doors are open will cause the doors to remain open. When contact **SEC** or door open push button **25** closes, door safety relay **DOX** is energized and relay **DO** becomes energized through contacts **SBR-2** and **DOX-1**. Power is supplied to relay **DE** through **LR-1** and **DO-3**, and contact **DE-3** opens to prevent relay **C** from becoming energized and closing power cannot be applied to the door operator motor and the doors remain open.

If the pressure-sensitive door edge and the door open push button are released before the expiration of the first time interval, the doors will remain open until expiration of the first time interval and then close. With both the safety edge contact, **SEC**, and door open push button **25** released, relay **DOX** is deenergized. When the first time interval expires, electronic timer contact **10e** closes. Relay **TDA** picks up or is energized, and contact **TDA-1** opens. Relay **DO** drops out or is deenergized, and contact **DO-2** opens breaking relay **DO**'s self-holding circuit. Contact **DO-1** opens and causes timer **10** to reset and reopen contact **10e**. Relay **TDA** drops out, but relay **DO** cannot pick up again when contact **TDA-1** closes because contact **DO-2** is open. Door operator pilot relay **DE** drops out when **DO-3** opens, and door close power relay **C** picks up when **DE-3** closes. Thus, door closing power is applied to the door motor.

If the safety edge contact, **SEC**, or door open push button **25** is released after the expiration of the first time interval, the doors close immediately upon such release. With either the safety edge or door open push button being operated with the doors open, relay **DOX** is

energized. The first time interval expires because the initiating circuit for electronic timer 10 is closed between terminals 10c and 10d through contacts DOL-1, EE-2 and DO-1. When the time interval expires, electronic timer contact 10e will close and relay TDA will become energized to open contact TDA-1, but relay DO cannot drop out because it is being held energized through contacts SBR-2 and DOX-1. Since relay DO cannot drop out, contact DO-1 cannot open to interrupt the initiating circuit for electronic timer 10 between terminals 10c and 10d. Contact 10e remains closed, relay TDA remains picked up, and contact TDA-1 remains open. As soon as both the pressure-sensitive door edge and door open push button are released, relay DOX will drop out and contact DOX-1 will open. Relay DO will drop out immediately because contact TDA-1 has been opened. When relay DO drops out, relay DE drops out, and relay C picks up as explained previously, and the doors close immediately.

If the safety edge contact, SEC, or door open push button 25 is operated while the doors are closing, the doors reopen fully. Operating either of these two energizes relay DOX, and contact DOX-1 closes to energize relay DO through contact SBR-2 which becomes self-holding through contact TDA-1 and DO-2. Relay contact DO-3 closes to energize relay DE through contact LR-1 and becomes self-holding through contacts SBR-3, DE-1 and DOL-2. Relay contact DE-3 opens to de-energize relay C. Contact DE-2 closes to energize relay O through contact C-2 and open limit switch OL. When relay O is energized, the door operator motor operates in the opening direction at normal speed until the doors are fully open.

Interruption of the photoelectric unit beam has different results under different conditions which are as follows.

Interruption of the photoelectric unit beam the first time at a floor other than the dispatching floors reduces the "door open" time from a first time interval to a second, shorter interval. Interrupting the photobeam causes photoelectric amplifier output relay contact 7b to close, thus energizing relay EE. Contact EE-3 opens, and relay DT is deenergized through the interruption of its self-holding circuit including contacts DO-4, DT-3 and EE-3. Contact EE-2 opens to interrupt the initiating circuit between terminals 10c and 10d of electronic timer 10, and timer 10 resets instantaneously. Contact DT-1 opens to disconnect the first time interval resistor 8 from the timing range terminals 10a and 10b of electronic timer 10. Contact DT-2 closes connecting the second time interval resistor 9 to the timing range terminals 10a and 10b of electronic timer 10. When the photobeam is cleared, contact 7b reopens, relay EE is deenergized, contact EE-2 closes to reestablish the initiating circuit between terminals 10c and 10d of electronic timer 10, and the electronic timer begins timing out the shorter time interval.

Each subsequent operation of the photoelectric beam at a floor other than the dispatching floors extends the door open time for the second time interval measured from the time of restoration of the beam. Each time the beam is subsequently interrupted, contact 7b closes to energize relay EE. Contact EE-2 opens to interrupt the timer initiating circuit between terminals 10c and 10d and the electronic timer resets instantaneously. When the photobeam is restored, contact 7b reopens; relay EE deenergizes and contact EE-2 closes to again complete the initiating circuit of the electronic timer. (Relay DT has previously been deenergized and, therefore, contact DT-2 is closed to connect the second time interval resistor 9 across the timer's timing range terminals.)

When the elevator is at a dispatching terminal, any interruption of the photoelectric beam before the dispatching interval has expired will not cause the door open time to be transferred from the first time interval to the

second time interval. When the car is at the top dispatching floor, brush 3 makes contact with segment 4a, causing TFL to energize. When the car is at the bottom dispatching terminal, brush 3 makes contact with segment 4b, causing relay 1FL to energize. As the car approaches a dispatching terminal, relay DT is energized through contacts DO-4 and DCL-1 and becomes self-holding through contacts DO-4, DT-3 and EE-3 just as at any intermediate floor. When the car is adjacent the dispatching floor level, either relay TFL or 1FL is energized. At the top dispatching terminal, relay contact TFL-1 closes to further retain relay DT energized through contact 12. At the bottom dispatching terminal, contact 1FL-1 closes to further retain relay DT energized through contact 13. Thus, the interruption of the photobeam and the corresponding opening of contact EE-3 does not cause relay DT to become deenergized as long as contact 12 remains closed when the car is at the top dispatching terminal or as long as contact 13 remains closed when the car is at the bottom dispatching terminal. If relay DT does not become deenergized, contact DT-1 remains closed causing the first time interval resistor 8 to be connected to the electronic timer's timing range terminals 10a and 10b. Contact 12 remains closed until the dispatching time interval expires at the top dispatching terminal and contact 13 remains closed until the dispatching time interval expires at the bottom dispatching terminal. Each interruption of the photobeam extends the door open time for the first time interval measured from the time of restoration of the beam.

If the doors are fully open at a dispatching floor after the dispatch interval has elapsed, each interruption of the photoelectric unit beam extends the door open time by the second time interval measured from the restoration of the beam. When the car is at the top dispatching terminal, relay DT is retained energized by a circuit through contacts TFL-1 and 12 and by a circuit through contacts DO-4, DT-3 and EE-3. When the dispatching interval elapses at the top terminal, contact 12 opens and remains open until the car leaves this terminal floor. Relay DT now remains self-holding only through contacts DO-4, DT-3 and EE-3. Any subsequent interruption of the photobeam causes contact EE-3 to open. The first time that contact EE-3 opens, relay DT is deenergized; resistor 8 is disconnected by the opening of contact DT-1, and resistor 9 is connected by the closing of contact DT-2 across the timing range terminals 10a and 10b of electronic timer 10. A similar operation holds true when the car is at the bottom dispatching terminal, wherein contact 13 opens when the dispatching interval elapses at the bottom dispatching terminal.

If the photocell beam is interrupted at any floor while the doors are closing, the rate of door closing is reduced to the lowest speed for which the door operator is adjusted, and the doors continue to close at the slow speed. When the beam is restored the doors resume normal closing speed, and may again slow down if the beam is re-interrupted. When the doors are closing and their position is somewhere between the fully open and fully closed positions, the relays DOL, DCL, LR and C are in an energized condition. All other relays are deenergized at this time. When the beam is interrupted, contact 7b closes and relay EE is energized. Contact C-1 is open and, therefore, the closing of contact EE-1 cannot cause relay DOX to become energized. Since relay DOX cannot become energized, relay DO remains deenergized, and relay DE will remain deenergized. If relay DE cannot become energized, relay C will remain energized. Relay contact EE-4 closes, causing slow speed adjustment resistor 20 to be connected across the door operator motor armature 18 through contact C-4. When resistor 20 is connected across armature 18, a greater amount of current is caused to flow through resistor 19 which increases the voltage drop across resistor 19 and decreases the voltage across armature 18. With less volt-

age applied to the door motor armature, the speed of door operating motor is reduced. The doors will continue to close at slow speed as long as the photobeam is interrupted as contact EE-4 remains closed. When the beam is restored, contact 7b opens and relay EE is deenergized. Contact EE-4 opens to disconnect resistor 20 from across armature 18 and normal armature voltage is applied to the door operator motor with the result that the doors resume their normal closing speed. Each subsequent operation of the photobeam causes contact EE-4 to close and place resistor 20 across armature 18 to reduce the door closing speed as long as the photobeam is interrupted.

10 Interruption of the photoelectric beam when the doors are fully open causes contact 7b to close and disables the door closing operation until the beam is reestablished. Relay EE becomes energized through 7b and contact EE-1 closes to energize relay DOX through contact C-1. Contact EE-2 opens to interrupt the initiating circuit for electronic timer 10 between its terminals 10c and 10d, thus preventing timer 10 from timing out and closing contact 10e. Relay DO becomes energized through SBR-2 and DOX-1 and becomes self-holding through contacts TDA-1 and DO-2. Relay DE is energized through contacts LR-1 and DO-3, and contact DE-3 opens to prevent relay C from becoming energized. If relay C is not energized, door closing power cannot be applied to the door operator motor armature, and the doors remain open. When the photobeam is reestablished, contact 7b opens to deenergize relay EE. Contact EE-1 opens to deenergize relay DOX and contact EE-2 closes to establish the initiating circuit between terminals 10c and 10d for electronic timer 10 through contacts DOL-1 and DO-1. (Timer 10 begins to time out.) Contact DOX-1 opens, but relay DO remains energized through TDA-1 and DO-2. When timer 10 times out, contact 10e closes to energize relay TDA. Contact TDA-1 opens to deenergize relay DO and contact DO-1 opens to interrupt the initiating circuit between terminals 10c and 10d of electronic timer 10 and the timer resets instantaneously. Contact 10e reopens and relay TDA drops out to cause contact TDA-1 to close, but relay DO cannot pick up again because contacts DO-2 and DOX-1 are now open. Contact DO-3 opens to deenergize relay DE and contact DE-3 closes to energize relay C through contact O-1 and switch CL. When relay C is energized, door closing power is applied to the door operator motor and the doors close at normal speed.

The pressure-sensitive door safety edge contact SEC or door open push button 25 may operate in the usual fashion whether the doors are closing at regular speed or at slow speed. As described above, operation of safety edge contact SEC or door open push button 25 causes relay DOX to become energized to remove closing power from the door operator motor. In addition, contact DE-2 closes to energize relay O to apply opening power to the door operator motor.

There is no circumstance under which the fully open doors may start to close if the pressure-sensitive door edge or the door open button is actuated, or if the photoelectric beam is interrupted.

We claim:

1. In a control system for the door of an elevator

which serves a plurality of floors, apparatus comprising: means for opening and closing said door; a timer responsive to opening movement of said door to initiate a timing period and to generate a signal actuating said door closing means at the end of said period, said timer having two timing circuits with different timing periods; means for selecting the longer of said timing periods on opening said door; a door time transfer circuit for selecting the shorter of said timing periods; means for sensing passage of a person through said open door; and means responsive to said sensing means for actuating said transfer circuit to select the shorter of the timing periods and reduce the door open time upon passage of a person through the door.

15 2. The elevator door control system of claim 1 wherein said elevator serves a terminal floor and including means responsive to the presence of said elevator car at said terminal floor to maintain selection of said longer timing circuit; a source of elevator dispatching signals; 20 and means responsive to receipt of a dispatching signal for modifying said door timer transfer circuit to respond to passage of a person through said door actuating the door timer transfer circuit to select the shorter of the timing periods.

25 3. The control system of claim 1 including further means responsive to said sensing means for reducing the door closing rate while an object is in the open door.

4. The elevator control system of claim 1 wherein said door time transfer circuit includes a relay having normally open and normally closed contacts and said timer has two timing circuits, one connected with the timer through the normally open contacts and the other connected with the timer through a normally closed contact of said door time transfer relay, the means responsive to the sensing 35 means effecting a reversal of condition of the relay and said contacts.

5. The control system of claim 4 wherein a circuit for said relay is completed energizing the relay upon arrival of the car at a floor, closing the normally open contacts 40 and wherein the timing circuit for the longer timing interval is connected with the timer through the normally open contacts, said relay having a holding circuit including a contact responsive to said sensing means and opened on passage of a person through said door, deenergizing 45 said relay and connecting the timing circuit for the shorter period with the timer through the normally closed contacts.

6. The control system of claim 5 including a terminal holding circuit connected in parallel with the holding circuit for said relay, said terminal holding circuit including contacts opened upon receipt of a dispatch signal from a source.
